UNITED STATES PATENT OFFICE.

ALBERT EDWARD GRANT, OF NEW YORK, N. Y., ASSIGNOR, BY MESNE ASSIGNMENTS, TO GRANT OIL BURNER CORPORATION, OF WILMINGTON, DELAWARE, A CORPORATION OF DELAWARE.

OIL BURNER.

Application filed October 15, 1923. Serial No. 668,568.

To all whom it may concern:

Be it known that ALBERT EDWARD GRANT, a subject of the King of Great Britain, residing at 3305 Broadway, New York, N. Y., has invented new and useful Improvements in Oil Burners, of which the following is a specification.

My invention relates to oil burners.

The object of my invention is to provide a device of very simple construction that is adapted to spray or atomize oil in providing a fuel mixture for use in furnaces of various kinds.

The novel features of my burner are set forth in the drawings and following specifications in which the construction and operation of the burner is clearly described and the novel features specified in the claims.

Figure 1 is a longitudinal sectional view of a burner embodying the construction and invention.

Figure 2 is an end view, the air and oil passages being indicated in dotted lines.

A, indicates the body portion of the burner which is provided with a central passage A' for steam and two passages B and C for air and oil respectively, which are preferably located diametrically opposite each other and at equal distance from the steam passage A'.

The inlet to the air passage is controlled by a valve D and the inlet to the passage C is also controlled by a valve E but is used only for the purpose of cutting off the oil supply to the burner and not to regulate the flow of oil thereto.

The body portion A is provided with a uniform thread F, formed in its outer cylindrical surface, and an adjustable cap G is fitted to engage therewith and is held in adjusted relation thereon by a lock-nut H. The steam outlet end of the body portion A, is formed with a conical projection I and the steam passage A' is reduced in diameter at its outlet J to provide a passage approximately $\frac{1}{20}$ of an inch in diameter for the size of burner illustrated which is drawn on a full size scale for one size of burner.

The air and oil passages are each about $\frac{1}{8}$ of an inch in diameter, and the burner outlet K is about $\frac{3}{16}$ of an inch in diameter.

A chamber L is found when the cap G is moved to open the oil and air passages B and C respectively, to serve as a mixing

chamber for the air and oil and the cap G also serves as a valve to control the flow of oil from the passage C to the chamber L, and to some degree to control the flow of air from the air passage B. The cap is formed with a conical seat M to contact with the conical projection I to form a valve by means of which both the air and oil flowing to the outlet K may be simultaneously controlled by causing the cap to move longitudinally on the body portion and contact with said projection without entirely closing the air and oil passages B and C. N indicates a source of oil supply and O a pipe leading therefrom to the oil passage C.

The operation of the device is as follows:

Assuming steam or air under pressure to be flowing through passage A', with valves D and E wide open and cap G positioned relative to the body portion A as shown: The steam flowing through outlet J, expands in passing through the combining tube and creates a rarefied atmosphere in chamber L which at once draws air from passage B and discharges it through outlet K but no oil will be lifted to the burner as the air is lighter than the oil and supplies enough to the chamber L to prevent oil from rising to the burner. If now, the air valve D is partly closed the steam cannot draw enough air to the chamber L to prevent a low pressure therein and immediately oil is drawn from the reservoir N by suction and flowing into chamber L and thence to passage P is mixed with air from passage B and sprayed by the steam into the atmosphere where the full mixture is ignited and burned.

It will be understood that the cap G serves as a throttling valve for both air and oil and by properly adjusting the cap valve and air valve D in complementary relation, and also controlling the steam pressure and consequently the volume thereof flowing relative to the flow of oil, a very perfect operation of the burner can be attained.

Having thus described my invention I claim as new:

1. An oil burner of the character described comprising a body portion having an unobstructed central steam passage extending entirely therethrough and an oil and an air passage located diametrically opposite to each other at an equal distance from said steam passage, means for controlling the flow of air through said air passage and a

cap adjustable on said body portion adapted to close communication between said steam passage and said air and oil passages.

2. An oil burner comprising a body por-

tion having an unobstructed central passage extending therethrough and provided with an extension, a cap carried by said body portion having an outlet arranged in alignment with said central passage and of greater area, said body portion having an air and an oil passage communicating with said outlet and means for restricting the flow of air through said air passage; said body portion and cap forming a chamber in open communication with said outlet and also forming a valve to close said outlet.

3. An oil burner comprising a body portion having an unobstructed central passage extending therethrough and provided with an extension, a cap carried by said body portion having an outlet arranged in alignment with said central passage and of greater area, said body portion and cap forming a chamber in open communication with said outlet and also forming a valve to close said outlet, means for holding said cap in adjusted position on said body por-

tion; said body portion having an air and an oil passage leading to said chamber and means for restricting the flow of air through said air passage.

4. An oil burner comprising a body portion having an unobstructed central passage extending therethrough and provided with an extension, a cap carried by said body portion having an outlet arranged in alignment with said central passage and of greater area, said body portion having an air and an oil passage communicating with said outlet and means for restricting the flow of air through said air passage; said body portion and cap forming a chamber in open communication with said outlet and also forming a valve to close said outlet, and means for holding said cap in adjusted position on said body portion, the area of said outlet being approximately equal to the sum of areas of the outlets of the steam, air and gas passages.

In testimony whereof, ALBERT EDWARD GRANT has signed his name to this specification this 26th day of September 1923.

ALBERT EDWARD GRANT.
